UNITED STATES PATENT OFFICE.

LUIS DIAZ HIDALGO, OF HABANA, CUBA.

CANE MILL.

Application filed July 21, 1920. Serial No. 397,889.

To all whom it may concern:

Be it known that I, LUIS DIAZ HIDALGO, a citizen of Cuba, residing at Habana, in the Republic of Cuba, have invented a new and useful Cane Mill, of which the following is a specification.

The device forming the subject matter of this application is a cane mill and the object of the invention is to improve the mechanism whereby the upper roller is held under hydraulic pressure.

In the drawings:—Figure 1 is a top plan; Figure 2 is a vertical longitudinal section wherein parts are shown in elevation; Figure 3 is a fragmental transverse section depicting the means whereby the movement between parts of the hydraulic pressure member is prevented.

As usual, the mill comprises a frame including a base 1 and standards 2 secured to the base, the standards being surmounted by caps 3 held in place by bolts 4. Vertical guideways 5 are fashioned in the standards 2.

The numeral 12 marks a lower shaft supported at 11 for rotation within the guideways 5. A bottom roller 19 is mounted on the shaft 12 to rotate with the shaft.

Upper bearings 21 are mounted to move in the guideways 5 of the standards 2. The numeral 24 designates a power-driven upper shaft journaled in the bearings 21. A roller 34 is carried by the shaft 24 and rotates therewith, the roller 34 being of considerably less diameter than the bottom roller 19.

The caps 3 are provided with vertical passages 37 enlarged at their upper ends to form chambers 38. The caps 3 are provided with circumferentially spaced lugs 39 projecting into the chambers 38. In each chamber 38 is located a head 40 having eyes 41 whereby it may be manipulated, the head having lugs 42 engaged beneath the lugs 39 and of such size as to move vertically between the lugs 39 when the head 40 is rotated so that the lugs 42 are no longer beneath the lugs 39. The head 40 is supplied with a reduced piston 43.

A cylinder 44 is seated in the chamber 38 and includes a reduced neck 45 extended into the passage 37. The cylinder 44 is adapted to slide vertically on the piston 43. A packing 55 is held by a plate 56 and a securing member 57 to the lower end of the piston 43 and has a depending flange bearing against the side wall of the cylinder 44 to afford a fluid-tight joint. The cylinder 44 includes

a hollow member 47 located partly in the passage 37 and held upon the reduced neck 45 of the cylinder by securing elements 46. A foot 48 is threaded for adjustment into the member 47, as indicated at 49 and has in its lower end a concaved seat 50 adapted to cooperate with a convexed block 51 mounted on the bearing 21. In order to prevent the foot 48 from rotating in the member 47 of the cylinder 44, notches 52 are formed in the edge of the foot 48, as shown in Figure 4, any notch being adapted to receive a locking strip 53 attached to the lower end of the member 47 of the piston 43 by a securing element 54.

Rotation is imparted to the shaft 24 and to the upper roller 34. The cane, passing between the rollers 34 and 19, imparts rotation to the roller 19.

When it is desired to adjust the effective length of the movable member of the hydraulic press, the part 48 may be threaded upwardly or downwardly in the part 47. When the aforesaid adjustment has been made, the locking strip 53 may be seated in one of the notches 52 of the member 48, the strip being attached to the element 47 by means of the securing element 54.

Should it be desired to remove the cylinder 44, the head 40 may be rotated until its lugs 42 no longer are beneath the lugs 39 which project into the chamber 38. Then, the head 40 may be removed, the lugs 42 on the head passing upwardly between the lugs 39 on the cap 3.

When the mill is in operation, the foot 48, the member 47 and the cylinder 44 are in almost continuous vertical movement. In order to permit the aforesaid movement, the caps 3 are provided at their inner sides with vertically elongated slots 58 receiving nipples 59 which communicate with the cylinders 44, the nipples being carried by the cylinders. The main pressure pipe is denoted by the numeral 60 and is connected with the nipples 59 by flexible tubes 61, to the end that the cylinders 44 may move vertically with respect to the pipe 60, the latter element being fixed, ordinarily.

Having thus described the invention, what is claimed is:—

1. A hydraulic press comprising a movable member made up of two parts threaded together to adjust one of said parts with respect to each other, and a locking device

connecting said parts, releasably, to prevent threaded movement therebetween.

2. A hydraulic press comprising a frame having a cavity, there being lugs on the frame, the lugs projecting into the cavity, a head in the cavity and provided with a fixed piston, the head having lugs engaged with the lugs on the frame, the head being rotatable, whereby the lugs on the head may pass upwardly between the lugs on the frame when the head is raised, a cylinder slidable in the cavity and slidable on the piston, and means for supplying pressure to the cylinder.
- 15 3. A hydraulic press comprising a frame having a cavity, there being lugs on the frame, the lugs projecting into the cavity, a head in the cavity and having lugs engaged beneath the lugs on the frame, the head being rotatable to dispose the lugs thereof out of alinement with the lugs on the frame and to permit a removal of the head, a member slidable in the cavity, and means for supplying pressure to the space between the said member and the head, said member comprising upper and lower parts threaded together for adjustment, and means on said parts for holding them releasably against relative threaded movement.
- 20 4. In a device of the class described, a main member having a passage enlarged at one end to form a chamber, said member being provided with circumferentially spaced

lug 35 projecting into the chamber, a head having lugs engaged beneath the lugs of said member, the head having a reduced piston, a cylinder seated in the chamber and movable therein, the cylinder receiving the piston, the cylinder having a reduced neck 40 extended into the passage, a hollow member slidable in the passage, means for securing the hollow member to the reduced neck of the cylinder, a foot threaded into the hollow member and provided with a concaved seat, the foot being provided in its end with a notch, a locking means secured to the hollow member and engaged with the notch to hold the foot against rotation, a convexed pressure member cooperating with the seat of the foot, and means for supplying pressure 45 to the movable cylinder.

5. A hydraulic press comprising a fixed piston, a cylinder slidable on the piston and including parts threaded together for adjustment, means for holding said parts 55 against relative threaded movement, and means for supplying pressure to the cylinder to cause it to move with respect to the fixed piston.

In testimony that I claim the foregoing 60 as my own, I have hereto affixed my signature in the presence of two witnesses.

LUIS DIAZ HIDALGO.
